CLAIM

The ornamental design for a football helmet tent, as substantially shown and described.

DESCRIPTION

FIG. 1 is a right side elevational view of the football helmet tent;

FIG. 2 is a left side elevational view thereof;

FIG. 3 is a front view of the football helmet tent;

FIG. 4 is a top plan view thereof;

FIG. 5 is a bottom plan view thereof; and,

FIG. 6 is a rear view of the football helmet tent.

The broken lines shown are for illustrative purposes only and form no part of the claimed design.
